CLAIM

The ornamental design for a wireless communications device, as shown and described.

DESCRIPTION

FIG. 1 is a front perspective view of a wireless communication device showing our new design.

FIG. 2 is a front view of the wireless communication device of FIG. 1.

FIG. 3 is a rear view of the wireless communication device of FIG. 1.

FIG. 4 is a top view of the wireless communication device of FIG. 1.

FIG. 5 is a bottom view of the wireless communication device of FIG. 1.

FIG. 6 is a left-side view of the wireless communication device of FIG. 1; and,

FIG. 7 is a right-side view of the wireless communication device of FIG. 1.

(Continued)

The characters shown in broken lines in FIGS. 2 and 3 form no part of the claimed design.

1 Claim, 7 Drawing Sheets
